(57) **CLAIM**

The ornamental design for an ink tank for printer, as shown and described.

DESCRIPTION

FIG. 1 is a front view of an ink tank for printer showing our new design;

FIG. 2 is a rear view thereof;

FIG. 3 is a top plan view thereof;

FIG. 4 is a bottom plan view thereof;

FIG. 5 is a left side view thereof;

FIG. 6 is a right side view thereof;

FIG. 7 is a front and bottom perspective view thereof; and,

FIG. 8 is a rear and top perspective view thereof.

The broken lines shown in the drawings are for illustration only and form no part of the claimed design.
